US0D1087194S

(12) **United States Design Patent** (10) **Patent No.:** **US D1,087,194 S**
(45) **Date of Patent:** **** Aug. 5, 2025**

(54) **ARTIFICIAL INTELLIGENCE ROBOT**

(71) Applicants: **Hyundai Motor Company**, Seoul (KR); **Kia Corporation**, Seoul (KR)

(72) Inventors: **Ji A Lee**, Seoul (KR); **Byeong Cheol Lee**, Seoul (KR); **Dong Han Koo**, Seoul (KR)

(73) Assignees: **Hyundai Motor Company**, Seoul (KR); **Kia Corporation**, Seoul (KR)

(**) Term: **15 Years**

(21) Appl. No.: **29/886,878**

(22) Filed: **Mar. 14, 2023**

Related U.S. Application Data

(63) Continuation of application No. 35/509,365, filed on Nov. 15, 2019 (U.S. filing date under 35 U.S.C. 384), and having an international filing date of Nov. 15, 2019.

(30) **Foreign Application Priority Data**

May 28, 2019 (KR) 30-2019-0025349

(57) **CLAIM**

The ornamental design for artificial intelligence robot as shown and described.

DESCRIPTION

FIG. 1 is a perspective view thereof;

FIG. 2 is a front view thereof;

FIG. 3 is a back view thereof;

FIG. 4 is a left view thereof;

FIG. 5 is a right view thereof;

FIG. 6 is a top view thereof;

FIG. 7 is a bottom view thereof; and,

FIG. 8 is a view showing the artificial intelligence robot in a state of use thereof.

1 Claim, 8 Drawing Sheets
